UNITED STATES PATENT OFFICE.

WILLIAM WRIGHT, OF CHICAGO, ILLINOIS, ASSIGNOR TO E. PAYSON SMITH, OF SPRINGFIELD, ILLINOIS.

BRAKE-GEAR HOUSING.

Application filed April 10, 1926. Serial No. 101,158.

My invention relates to a gear housing adapted to be secured to the end sill of a car underframe, comprising a two piece member so constructed as to provide a housing possessing strength and rigidity; wherein assembly of the gear elements may be readily accomplished, and whereby attachment to a car underframe member may be easily made.

10 My invention and its objects will be readily comprehended from the detailed description of the accompanying drawings, wherein:—

Figure 1 is a top plan view of my improved housing shown attached to the end sill of a car underframe, a portion of the end sill being shown in section.

Figure 2 is a transverse section taken substantially on the line 2—2 of Figure 1.

20 Figure 3 is a perspective view of the bottom member of the housing.

Figure 4 is an end elevation of the housing and gear elements therein, looking at the outer end of the housing and outer face 25 of the end sill.

Figure 5 is a perspective view of the top member of the housing.

Figure 6 is a side elevation of the housing with the gear elements and brake-staff omitted; the end sill being shown in section.

My invention, as exemplified in the drawings, comprises a housing composed of two members, consisting of a top member 10, see Figure 5, the main portion whereof is practically of rectangular configuration, see Figure 1, and is adapted to be secured to the lower flange of the end sill member 11 of the car underframe so as to be disposed transversely therebeneath. The main body portion, intermediate of its ends, is provided with laterally disposed lobes 12, 12 apertured to permit being riveted or otherwise secured to the lower flange of the end sill as shown at 13. The forward or outer end of 40 the top member 10 of the housing, namely forward of the lobes 12, 12, is provided with depending sides or portions 14, 14 adapted to be disposed at diametrically opposite sides of the drive gear 15 which is 45 controlled by the brake-staff 16. The forward or outer end of the housing is preferably provided with the offset arcuate portion 17 which overlaps the top of the drive gear 15; this gear 15, like the driven gear 50 18, is horizontally disposed.

The inner or rear end of the top member 10 is provided with a pair of extensions arranged to extend beyond the plane of the perimeter of the driven gear 18; that is to say, the rear or inner end of the top member 10 adjacent to one longitudinal side is provided with the obliquely disposed extension 19; while the other longitudinal side is provided with the substantially right angularly disposed extension 20; the extensions 19 and 20 being provided with downwardly disposed ends 21 and 22, respectively.

For purposes of strength, the marginal edges of the top member are preferably flanged, as are also the downwardly disposed ends 21 and 22.

The upper surface of the top member 10, at a point adjacent to the portion having the lobes 12, 12 is provided with an upstanding portion or wall 23, which is adapted to extend flush with the rear side of the end sill 11 and to be attached thereto, by means of the rivets 24 or otherwise. The upstanding portion 23 is reenforced by rearwardly sloping webs 25 and 26; the web 26 being shown extending out toward the end of the extension 19 so as to reenforce the latter and also brace the housing against the pulling strains of the brake-chain; that is to say, the webs 25 and 26 act as compression members whereby any tendency toward upward tilting of the rear end of the housing induced by the pull of the chain will be transmitted to the rear side of the end sill 11. 90 The top member 10, along the forward longitudinal side of the portion provided with the lobes 12, 12, is preferably provided with a transverse rib 27 which is adapted to come flush with the forward edge of the lower flange of the end sill 11; that is to say, the rib 27 and the upstanding portion 23 are spaced apart a distance just sufficient to receive the lower flange of the end sill 11 therebetween, as shown in Figures 2 and 6. 95

The forward end of the top member 10 is provided with a suitable opening to receive the upper end of the hub 28 of the drive gear 15; the hub 28 being also formed to receive a squared portion of the brake-staff 16 so as to cause the drive gear 15 to rotate with the shaft. The lower end of the hub 28 of the drive gear is preferably flanged inwardly as shown at 29 to provide a pocket for the end of the brake-staff 16; 100 105 110

while permitting the reduced cylindrical end 30 of the brake-staff to be disposed therethrough. The top member at a point rearward of the end sill is suitably apertured to receive one end of hub 31 of the driven gear 18, see Figure 2, the hub on the lower side of the driven gear being extended with a portion thereof preferably squared to receive the chain-drum or spool 32 and cause the latter to rotate with the driven gear 18.

The drive and driven elements are held in position by means of the lower member 33 shown in detail in Figure 3 and consisting of the forward rectangular portion 34 having downwardly extended sides 35, 35. This portion 34 of the bottom member 33 is intended to be disposed between the depending portions 14, 14, of the top member, with the depending ends or flanges 35, 35 extending flush with the inner sides of the depending ends 14, 14; the depending ends 14 and flanges 35 being apertured to permit the members to be readily secured together by means of rivets or otherwise. This forward rectangular portion 34 of the bottom member 33 has a countersunk opening 36 to receive the lower end of the hub 28 of the drive gear 15 and thus provide a shoulder or rest therefor while permitting the reduced lower end 30 of the brake-staff 16 to extend therethrough as shown in Figure 2. The countersunk opening 36 will maintain the drive elements in proper position when the top and bottom member of the housing are secured together, because the lower end 29 of the hub 28 will rest on the annular shoulder 37 and thus prevent improper movement or play of the drive mechanism. Disposed rearwardly and downwardly from the inner longitudinal edge of the rectangular portion 34 is an arm 38 which terminates in the ramifications or portions 39 and 40 which in turn have upwardly disposed curving ends, as shown in Figure 3. The ramification 39 extends outward at an oblique angle and corresponds to the portion 19 of the top member 10; the end of the ramification being shown reduced and laps the inner side of the downwardly disposed end 21 of arm 19 and is suitably secured thereto. The ramification 40 extends substantially at right angles to the arm 38 and corresponds with the arm 20 of the top member; the upwardly extending end of the ramification is preferably also somewhat reduced and is made to lap on the inner side of the downwardly disposed end 22 of arm 20, to which it is suitably secured. The construction shown provides a more or less skeleton housing which, however, possesses ample strength while at the same time being comparatively light in weight; the top and bottom members being secured together at four widely spaced apart points

and a firmly and rigidly held supporting member or bottom provided; the top and bottom members being formed to receive the trunnions of the drive and driven elements and as a result easy assembly of the parts 70 is possible.

As is apparent from the construction shown, the bottom member is not only supported at widely separated points and at points to opposite sides of the axis of the drive element, but also at points beyond and in advance of the axis of the driven element, relative to the direction of the pull of the chain.

The invention has been disclosed in what 80 is believed to be the simplest embodiment thereof and has been described in terms employed merely as terms of description and not as terms of limitation as modifications are possible without, however, departing 85 from the spirit of my invention.

What I claim is:

1. A brake gear housing, comprising a top member, the forward end whereof has downwardly disposed sides, the rear end consisting of diverging portions terminating in downwardly disposed ends, while the intermediate portion is laterally extended at diametrically opposite points for attachment to the bottom of a car end-sill, and a bottom member, the forward end being adapted to be disposed between the downwardly disposed sides of the top member, while the rear end is offset and terminates in diverging portions having upstanding ends adapted to be secured to the downwardly disposed ends of the diverging portions of the top member.

2. A brake gear housing, comprising a top member and a bottom member, the top member at one end consisting of diverging portions, the forward end and said diverging portions having, respectively, downwardly disposed sides and ends, a pair of transversely extending and spaced apart upstanding portions adapted to engage opposite sides of the bottom flange of a car end-sill, while the portion of said top member intermediate of said upstanding portions is extended laterally beyond the normal sides of the top member to provide attaching portions to the bottom of the car end-sill, the bottom member having one end provided with diverging portions terminating in upstanding ends, said bottom member being adapted to be secured between the downwardly disposed sides and ends of the top member.

3. A brake gear housing, comprising a top member, one end whereof consists of portions diverging at different angles to the 125 longitudinal axis of the member, said member at an intermediate portion being provided with an upstanding end-sill engaging portion and laterally disposed attaching portions, reenforcing webs extending from said 130

upstanding portion to the ends of said diverging portions, and a bottom member, one end whereof consists of diverging portions having upstanding ends connected to the 5 diverging portions of the top member.

4. A brake gear housing composed of two members, the top member being provided with a lobe extending laterally from each side adapted to extend flush with and be secured to the bottom flange of a car end-sill, the end forward of the lobes being apertured and provided with downwardly disposed sides, while the rear end of the member terminates in diverging portions having 10 downwardly disposed ends, while the bottom member at its forward end is adapted to be disposed between and be secured to the downwardly disposed sides of the top member, the rear end terminating in diverging 15 portions having upwardly disposed ends adapted to be secured to the downwardly disposed ends of the diverging portions of the top member.

5. A brake gear housing, comprising a top member provided with diverging portions, the forward end and said portions having downwardly disposed ends, and a bottom member provided with diverging portions terminating in upwardly disposed portions 20 adapted to be secured to the ends of said top member portions while the forward end of the bottom member is adapted to be secured between the downwardly disposed ends of the forward end of the top member.

35 6. Brake gear housings having a drive element and a driven element mounted therein, comprising a top member and a bottom member, the corresponding ends of both members consisting of diverging extensions terminat-

ing beyond the perimeter of the driven element mounted between the members, the diverging extensions of both members and the other ends of the members being secured together.

7. Brake gear housings, comprising a top member, a bottom member, the corresponding ends of both members consisting of correlated diverging extensions terminating beyond the perimeter of the driven element mounted between the members, the diverging extensions of the two members being secured together, the other ends of the two members being secured together at diametrically opposite points relative to the axis of the drive element mounted between the members, and end sill engaging extensions sloping upwardly from the diverging extensions of the top member.

8. Brake gear housings, comprising a top member provided at an intermediate point 60 with lateral extensions to provide attaching points to a car end-sill, one end of the member consisting of two diverging extensions disposed beyond the perimeter of the driven element mounted in the housing, the diverging extensions and the other end of the member being provided with downwardly disposed portions, and a bottom member, one end whereof is attached to the downwardly disposed portions at the last mentioned end of the top member, while the other end of the bottom member consists of two diverging extensions having upwardly disposed portions attached to the downwardly disposed 65 portions of the diverging extensions of the top member.

WILLIAM WRIGHT.
